UNITED STATES PATENT OFFICE.

EDWARD E. CLEMENT, OF WASHINGTON, DISTRICT OF COLUMBIA, ASSIGNOR, BY MESNE ASSIGNMENTS, TO JAMES R. GARFIELD, TRUSTEE, OF CLEVELAND, OHIO.

TELEPHONE-EXCHANGE SYSTEM.

1,235,186.

Specification of Letters Patent. Patented July 31, 1917.

Application filed September 8, 1905. Serial No. 277,524.

To all whom it may concern:

Be it known that I, EDWARD E. CLEMENT, a citizen of the United States, residing at Washington, in the District of Columbia, have invented a certain new and useful Improvement in Telephone-Exchange Systems, of which the following is a specification, reference being had therein to the accompanying drawing.

10 My invention relates to telephone exchange systems, and has for its object the simplification and improvement of the central office apparatus used in such systems. It is a particular object of the invention to 15 avoid the use of individual answering jacks or plugs for incoming lines, and to employ in lieu thereof mechanical connecting devices through which incoming calls or trunk calls may be automatically distributed upon 20 idle connective circuits and before presumably idle operators.

Briefly stated, the invention comprises line-circuits provided with individual line-signal relays at the central office, each circuit connected to multiple contacts in a number of switches, which I shall hereinafter term primary selectors. When a line calls its relay acts to raise the potential of its test terminals in all of the switches to which it is multiplied. The switch-arms are constantly rotated and the first arm which encounters a contact of the line calling stops, and by means of a solenoid which it carries sticks a plug into an opening in the group of springs 30 associated with the test terminal, thereby performing the same functions performed by an operator when she inserts an answering plug into the jack of a calling line. Each primary selector switch forms the terminal 35 of a trunk, whose other end is connected to what I shall term a secondary selector switch, which is similar in its construction and operation to the primary selector switch, and contains multiple terminals of operators' 40 cord-circuits, the other terminals of which are plugs or jacks or similar manual switching means.

It will be obvious without further explanation that by this arrangement any incoming call may be distributed to any cord circuit in the exchange. Assuming for instance that we are dealing with an exchange of 50 10,000 lines, in which there are 100 operators; assume that each incoming line is multiplied ten times to the switches of as many

trunks; and that each cord circuit is multiplied the same number of times to as many trunk switches. A calling line may be picked up by any one of ten different primary selectors or trunk switches, and this in turn may pick up through its secondary selector any one of ten cord-circuits, hence the line has access to one-hundred cord-circuits, and if the distribution be such that the first group of trunks goes to the first cord-circuits of all the positions, the second group of trunks to the second cord-circuits, and so on, then the calling line has a possibility of access to every operator in the exchange.

My circuits are so arranged that during 70 conversation there is but one additional tap off the talking circuit, or one-half an additional bridge. Single supervision is all that is required by the operators, that which is commonly called the answering supervisory 75 being used in this case as a calling signal. The calling subscriber controls his own connection, absolutely, the called subscriber alone being subject to delay through failure of the operator to promptly disconnect. The 80 effect of this, however, is minimized by giving the called subscriber control of his own supervisory signal, so that he can at all times attract the attention of the operator.

The switch I employ comprises a shaft 85 constantly driven, a fixed collar on the shaft and a switch-arm carried thereby provided with a clutch by which it can be coupled to and uncoupled from the shaft with great quickness. Around the shaft is a circularly 90 arranged series of line-contacts, each pair of talking contacts having an associated test terminal controlled by the line-relay. The switch-arm consists of a tube fitted with spool-heads and containing a composite core 95 fitted to slide within it, the inner end iron and the outer end insulating material. The tube carries the windings constituting a solenoid and the whole is inclosed in a drawn metal shell of cylindrical shape opened at 100 one end to slip on over the spool-heads. The tube is firmly secured at its inner end to a ring freely rotating on the fixed collar of the shaft, and at its outer end to the spool-head. A pair of terminal studs for the solenoid 105 windings are firmly secured to the same spool-head and extend forwardly, passing through bushed openings in the end of the shell and threaded outside of the same to receive nuts holding in place spring-terminals, 110

which as the arm is rotated by the shaft sweep over the switch-contacts heretofore mentioned.

The specific form of selector switch briefly described above is not claimed herein, as it constitutes a separate invention. The claims in the present case will be directed to the system as such, in which this specific form of switch is incorporated for purposes of definition and not of limitation.

My invention is illustrated in the accompanying drawings wherein,

Figure 1 is a diagram showing a subscriber's station and a central station, also the trunk circuit and two selector switches. Fig. 2 is a similar diagram showing a cord-circuit and a subscriber's station with its central office equipment. Figs. 3 and 4 are a cross section and a plan view, respectively, of one switch. Fig. 5 is a diagram showing the distribution of lines and cords.

Figs. 6 and 7 are diagrams showing modified arrangements for the distribution of lines and cords.

I will first describe the selector switches and their mode of operation and then describe the circuits.

The selector switch shown in Figs. 3 and 4 comprises a constantly driven shaft X with a collar, carrying an individual arm X', which carries the contact x⁸ constantly sweeping over an annular series of line test-contacts x'. The contact x⁹ of the arm X' sweeps over a continuous ring x⁷. The shaft in the present case is shown as driven by a belt L and a pulley L', but it will be understood that the driving means may be of any suitable description. The several selectors are all driven by preference on or from the same shaft, so as to secure not only economy of power and transmission but perfect uniformity in speeds of the selector arms which may sweep over multiples of the same line.

The primary selector mechanism is shown at X', in Fig. 1, and comprises a sleeve or collar x¹⁰ with a flange, mounted loosely on the shaft and resting on the collar x¹¹ which is fast to the shaft. Within and serving as a bearing for the flange of the collar x¹⁰ is a collar x¹², which is also fast to the shaft. The movable collar x¹⁰ is fitted with a projecting tubular arm preferably of copper or brass, which carries the windings x¹³ and x¹⁴ upon it and the combination core and plug x¹⁵ within it, the arm being thus a solenoid with a plunger core. The windings are held in place by the two spool-heads x¹⁶ and x¹⁷. On the front spool-head x¹⁶ are two stud terminals x¹⁸ and x¹⁹ to the inner ends of which are attached the terminals of the windings x¹⁴ and x¹³, respectively. The solenoid is protected by the drawn metal dust-proof shell x¹⁶ which slides over the spool-heads and has two bushed open-

ings to pass the terminals x¹⁷ and x¹⁸. To the threaded ends of the terminals, projecting through the bushed openings, are fitted the contact springs x⁸ and x⁹, held in place by suitable nuts. On the plunger, and resting against the outer head of the magnet, within the case, is a helical coiled spring x¹⁹ by which the plunger is normally kept retracted toward the shaft as shown in the figure.

The function of this plunger is two-fold. In the normal or idle condition of the parts it serves as a coupling or clutch to hold the arm fast on the shaft, its end projecting into an opening or socket in the collar x¹² as indicated at x²⁰. When the arm is opposite a calling line terminal the plunger is thrown forward and its outer end enters the jack ring x⁷, the inner end at the same time leaving the socket in the collar, thus stopping the arm and simultaneously spreading the jack springs to form the necessary connections.

The inner end of the plunger x¹⁵ is of soft iron with a hard tip if necessary. Its outer end is of insulating material such as hard wood or fiber. The winding of the magnet is double, consisting preferably of layers which may be inner and outer. One terminal of the outer winding is connected to the contact spring x⁸, through the stud x¹⁷, the other terminal of the coil is grounded. One terminal of the inner winding of the magnet is connected to the contact spring x⁹, through the stud x¹⁸, the other terminal of the winding is also grounded. In this particular case I have grounded the shaft itself for convenience so it is only necessary to connect the two terminals of the coils which are to be grounded to the sleeve of the solenoid.

Of course these two windings of the solenoid may be put on the tube or sleeve in any desired fashion. The only requirement is that either winding when energized shall be able to pull and hold in the core, x¹⁵.

The solenoid or arm, X', is the one which picks out the line calling and connects it to a trunk, to the other end of which is connected a similar arm or solenoid, X², to pick out an idle cord-circuit. In construction, the latter solenoid is identical with that of the one just described, the only difference being in the winding of the magnet. Instead of having a double wound coil, it is only necessary to have a single coil, the two terminals of which are connected to the contact springs x²⁸ and x²⁹.

Having thus briefly described the construction and operation of the selector arms or solenoids, we may take up the circuits by which they are controlled. In Fig. 1, the subscriber's station shown at A' is equipped with the apparatus usually found in common battery installations, the principal

- parts being transmitter T, receiver R, hook H, ringer Q, and condenser C. The line wires from this station terminate in a line relay M through the contacts of a cut-off relay N. When the relay N is energized the line wires 1 and 2 are connected to the extensions 5 and 6, respectively, which terminate in multiple contacts in the banks of the different selector switches of the line group. Each line is multiplied in a certain percentage of these selector switches and also to the multiple jacks in the switch-board panels in front of the operators. In a group of selector switches the arms are set 15 radially around the shaft so that each line through its multiple contacts, is swept over during one revolution of the shaft as many times as there are switches in the group. Suppose for illustration there were ten 20 switches and the shaft made one revolution per second, then every one of the ten multiple contacts of a particular line in the bank would be swept over once in the second. By this arrangement the time in answering a 25 call or picking out a line is of very short duration. The back contact m' of the relay M is connected to the contact x' in the bank of the switch X' and also multiplied to contacts in the other switches of the same 30 group. The trunk wires 9 and 10 are connected to the bus contacts x^5 and x^6 , respectively. These contacts are common to all 35 of the line springs in the bank, so that when the plunger of the solenoid is operated any line in the bank can be connected to the trunk wires 9 and 10. The contact x^7 of the bank is connected to a normally open contact p^5 of the relay P⁰. The trunk wires 9 and 10 terminate in the relay S⁰ through 40 the normally closed contacts of the relay P⁰ which when energized connects the answering end of the trunk to the calling end. The trunk wires 15 and 16 of the calling end of the trunk terminate at the bus contacts x^{24} 45 and x^{25} , respectively, of X². The common contact x^{26} is connected to normally open contacts in the relays P⁰ and S⁰. The individual contacts x^{22} and x^{23} terminate the cord-circuit shown in Fig. 2.
- 50 The cord-circuits of the various operators are distributed among the various selector switches X² in the same manner as the line-circuits of the various subscribers are distributed among the selector switches X'. The distribution can be made as follows: The No. 1 cord-circuit of each of a certain set of operators is multiplied in the banks of a certain number of groups of secondary selector switches, and the number 2 cord-circuit for each of the same set of operators is multiplied in the bank of a different group of selector switches and so on, thus distributing the cord-circuits of each operator among a very large percentage of subscribers. Distribution similar to that in manual systems
- can also be had if desired, by connecting the cord-circuits of each operator to one group of selector switches, thus allowing a particular operator to attend to the wants of a certain class of subscribers. The distribution 70 can be varied in any manner and any particular class distribution effected. This is illustrated in Fig. 5, which shows the first scheme, whereby the primary selector switches have each 100 line terminals, and the secondary selectors each 10 cord terminals. Further reference will be made to this hereafter.
- Referring now to Fig. 2, the answering end of the cord-circuit has relay S and retardation coil I with bridged battery between them connected to trunk wires 21 and 22, respectively. The relay and coil furnish talking current for the calling subscriber, and the relay S controls the circuit of the signal lamp s^{20} and the solenoid X². The calling and answering ends of the cord are separated by the condensers C and C'. The calling end terminates in the plug P, to the tip and sleeve of which are connected, respectively, the bridged relays S' and S'', which furnish a path for battery-current to the called subscriber. The subscriber's station A' and central office line equipment are identical with those in Fig. 1 and need no 95 description.
- The operation of my system is as follows: The subscriber at station A', removing the receiver, closes the line-circuit, energizing the relay M through the contacts of the 100 relay N. The relay M in attracting its armature connects battery to the contact x' in the bank of the selector switch X' and also to its multiple contacts in the other switches of the same group by the following path: 105 battery, B, 12, m , m' , 13 to x' . The first solenoid or arm in passing around comes into contact with the spring x' and becomes energized by current flowing from x' through the outer winding x^{13} to ground. 110 The solenoid being thus energized the plunger x^{12} is drawn forward, the insulated end enters a ring x^7 and the other end leaves the notch x^{20} in the collar x^{12} , thus freeing the arm from the revolving shaft X. The insulated end of the plunger entering the ring x^7 closes the contact springs x^2 , x^5 and x^6 , x^8 , thereby connecting the calling line to the trunk wires 9 and 10. As soon as this connection is made the circuit of the cut-off relay N is closed by the following path: battery B, p^8 , p^7 , 10, x^6 , x^3 , 6, N, to ground. The relay N now becoming energized attracts its armatures, disconnects the relay M, and this in turn removes battery from 120 the contact x' . The solenoid X', being deprived of current through the winding x^{13} is kept energized through the closing of the circuit of the inner winding x^{14} by the following path: battery B, 14, s' , 8, 7, x' , 130

x^9, x^{18}, x^{14} to ground. The relay S^0 became energized when the trunk connection was effected by battery current flowing through the contacts p^7 and p^8 of relay P^0 over the sleeve side of the line No. 2 through the subscriber's station and back over No. 1 side of the line to No. 9 side of the trunk and through the contacts p and p' of the relay P^0 to ground through S^0 .

10 The calling subscriber is now connected to an idle trunk, and the next step in order is to pick out an idle cord in front of an operator who will then complete the connection in the regular manner. It will be noticed that the solenoid X^2 while rotating is inactive, that is, the winding of the coil is open, one terminal being connected to the normally open contact s^3 of the relay S^0 . This relay now being energized, the contacts s^3 and s^2 are closed and the terminal x^{29} of the coil is grounded and ready to pick out an idle cord in front of some operator.

Referring to Fig. 2 it will be noticed that the contact x^{21} of the bank is connected to battery through a normally closed contact of the relay S^2 and in series with normally closed contacts s^4 and s^5 of the relay S . When a cord is in use, that is, when it is inserted in a jack the relay S^2 is energized and the contact s^{12} is broken, disconnecting battery from the contact x^{21} of the bank and making it impossible for a solenoid to operate on a busy cord. The foregoing circuit being in series with contacts s^4 and s^5 of the relay S prevents more than one switch coming to rest on the same cord, for the relay S becomes energized immediately the cord is picked out, breaks apart the contacts s^4 and s^5 , and disconnects battery from the contact x^{21} . This contingency has to be provided for because the operator might not answer the call at once and the different switches sweeping around successively would find battery on connected test contacts, therefore

45 by tying up a number of them.

A ground now being placed on one terminal of the winding of the solenoid and the other terminal connected to the test wiper or contact, the switch is in condition to pick out an idle cord in front of one of the operators. In finding an idle cord, that is a test contact in the bank connected to battery through the cord-circuit relays, the circuit of the solenoid is completed by the following path: ground, $s^2, s^3, 17, x^{26}, x^{29}, x^{38}, x^{35}, x^{37}, x^{28}, x^{21}, 20, s^4, s^5, 26, s^{12}, s^{11}, 31$, to battery B. The plunger of the solenoid now springing forward closes the contacts x^{22}, x^{24} and x^{25}, x^{23} , connecting the trunk wires

55 15 and 16, respectively, to the wires 21 and 22 of the cord-circuit, Fig. 2. The instant this connection takes place, the circuit of the relay P^0 is closed by the following path: battery B, 27, I, 24, 22, $x^{23}, x^{25}, 16, P^0$, to ground. This relay now becoming energized attracts its armatures and connects the wires 9 and 10 to the wires 15 and 16 respectively thus completing the circuit from the calling subscriber to an idle cord. After this circuit is completed the relay S becomes energized by battery from the coil I through the sleeve side of the trunk to the calling subscriber's station back through the tip side of the trunk through the relay S to ground. When the relay P^0 became energized the relay S^0 was disconnected and in turn removed the ground from one terminal of the winding on the solenoid. Now in place of this ground, battery is connected direct through contacts, p^3 and p^4 of the relay P^0 and at the same time battery is disconnected from the other terminal of the winding through the contacts of the relay S and ground connected in its place. The circuit of the winding on the solenoid is now closed by the following path: battery B, 18, $p^3, p^4, 19, 17, x^{26}, x^{29}, x^{38}, x^{35}, x^{37}, x^{28}, x^{21}, 20, s^4, s^7, 25$, to ground, the battery connection simply being reversed. The solenoid X' in place of being kept energized by the relay S^0 is held so by the relay P^0 by the following path: battery B, 18, $p^3, p^4, 7, x^7, x^9, x^{18}, x^{11}$, to ground.

Referring again to Fig. 2 the relay S becoming energized closes the circuit of the signal lamp s^{20} by the following path: ground 25, $s^7, s^6, 28, s^{20}, 26, s^{12}, s^{11}, 31$, to battery B. The operator noticing the lamp glowing uses her listening key and asks the number of the line desired. Placing the

100 plug P into the jack J of the desired line she rings in the ordinary manner. This insertion connects the relays N and S^2 in series, the relay N attracting its armatures disconnects the line relay M and connects the calling line to the springs j and j' of the jack J. The relay S^2 becoming energized opens the contacts s^{11} and s^{12} extinguishing the lamp s^{20} and at the same time closing the circuit of the lamp s^{30} which continues to glow until the called subscriber answers. Upon answering he closes the line circuit and energizes the relay S' extinguishing the lamp s^{20} , notifying the operator that he has responded.

The reason for reversing battery through

115 the winding on the solenoid X^2 was to remove battery from the test contact x^{21} and so render it busy preventing other switches from stopping.

At the end of the conversation the calling

120 subscriber hanging up, the relay S becomes deenergized and ground is removed from the test contact x^{21} and battery connected instead, and as battery is also connected to the other terminal of X^2 it becomes deenergized and the plunger returning to its normal position under the tension of the spring x^{39} disconnects the trunk wires 15 and 16 respectively from the cord-circuit wires 21 and 22. As soon as this happens the

relay P^9 becomes deenergized and opens the contacts p^5 , and p^3 , releasing the solenoid X' which upon returning to its normal position under the influence of the spring x^{19} disconnects the calling line from the trunk and all the apparatus returns to its normal or starting position, the arms X' and X^2 again continuing to rotate as before. The called subscriber in hanging up deenergized the relay S' which again closes the circuit of the lamp s^{20} which upon glowing the second time notifies the operator that the conversation is finished, whereupon she withdraws the plug rendering that particular cord-circuit idle by placing battery on the test contact again.

From the foregoing description it will be noticed that the calling subscriber has absolute control over his connection at all times, and in case of a recall he simply hangs up and automatically disconnects himself from the cord-circuit and in taking down his telephone again he is automatically connected to another cord-circuit.

Referring to Fig. 5, I have therein laid out one scheme of distribution of the lines and cord circuits to the primary and secondary selectors. The arrangement is supposed to be applied to an exchange of 10,000 subscribers, and 10% of the lines, selectors, trunks, and plug circuits, are represented in the figure. The total number of trunks for the whole 10,000 lines, assuming 10% as the proper proportion of connective circuits to be provided, is 1000, each trunk having at the line end a primary selector X' and at the switchboard end a secondary selector X^2 . Each primary selector switch contains 100 line terminals, while each secondary selector contains 10² cord terminals. Each line and each cord has 10 multiples and I divide all the selector switches with their trunks into groups of 10. I may therefore call this very appropriately a decimal scheme of distribution. It is to be distinctly understood however that I do not limit myself to the particular numbers here set forth. I am quite well aware that in most exchanges the efficiency of trunks is proportional, roughly speaking, to the size of their groups, or to the scope of selection. In many cases with 10 trunks in a group each trunk will carry 75 calls per day; with 50 trunks in a group each trunk will carry 150 or more calls per day. I have shown 10 as a convenient multiplier; and I have eliminated the inequalities of distribution so far as the operators are concerned and their cord circuits; but the efficiency of the trunks between the selectors will vary somewhat with the number of line multiples, or the number of trunks in a group, and the cure for any congestion or drop in efficiency is simply to increase the number of trunks and selector switches in a group and consequently the number of line

multiples for that group. Here comes in the flexibility of the system, whereby any condition can be met.

In the left of Fig. 5 I have shown the individual trunks of the first group, X' , to which are connected lines from 1 to 100. In the right of the figure I have shown 9 lines, 9 pairs of selectors and 9 trunks, each symbolizing an entire group, and each so marked.

The line 1—2 is shown connected to the first group of primary selectors, and multiplied to the contacts 10, 20, 30, 40, etc., of the respective switches of that group. It will be observed that the switch arms of the group are all set around at different angles, so that they will sweep over the corresponding contacts in succession, since all the arms are being constantly rotated at the same speed by the same shaft. It is apparent that the line 1—2 or any line calling in the first group of 100 lines may be picked up by any one of the primary selectors X' and so put onto the corresponding one of the trunks. The arrangement of the cord circuits with regard to the secondary selectors is as follows. The first group of lines, with which I am at present dealing, I have determined to distribute among the various operators, of whom there are 100 in the exchange, using for that purpose the number one plug and cord circuit of each operator. In other words calls over number one group of lines are absorbed by the number one cord circuits along the board. I do not mean by this that all the number one cord circuits are taken up by the first group of lines. On the contrary, there are 100 of these number one cord circuits, one for each position, and these will take care of 1000 lines, or 10 groups, and these are precisely the 10 groups I have shown in Fig. 5. At the bottom of this figure there are shown 10 plugs, each with the cord circuit 21—22 extending up to one of the secondary selector switches X^2 in the first group, and each multiplied to a secondary selector in every one of the other groups on the right, the multiple connections being marked 210. Each of the 10 plugs is symbolic of a group of 10, just as each of the lines, trunks and selectors in the right of the figure is symbolic of a group of 10. Now suppose the line 1—2 is calling, and the first three primary selectors are already busy. The switch-arm of the fourth selector in due course reaches the contact of the calling line and stops thereon as we have previously determined. This puts the line on the fourth trunk and on the fourth secondary selector. This selector has access through the extension 21—22 to the group of plugs P^{10} , which would be the number 1 plugs on the tables of operators from Nos. 31 to 40. We will assume that the number 1 plugs of operators 31, 32 and 33 are engaged.

100
105
110
115
120
125
130

The arm of the secondary selector will stop then on the terminal of the cord 21—22 leading to the number 1 plug on position number 34. Thus it will be perceived that this line by the double distribution, first to a certain trunk and then to a certain cord circuit, has reached an arbitrary position on the switchboard which bears no apparent relation to its number whatever, similarly by following through the different primary and secondary selectors, we will find it sometimes on the first section and sometimes on the last position of the board. Any line from No. 1 to No. 1000 gets this same distribution on the No. 1 plugs, and since we are dealing with lines in blocks of 1000, it would seem that averages would hold and sufficient flexibility would be attained to prevent any but a negligible number of "lost calls."

Having thus described the principal scheme, I should point out one or two modifications which are almost obvious and whose importance demands that they be not forgotten. It should be observed first that instead of carrying the lines in groups, the first group of 100 lines multiplied to the first group of 10 primary selectors, and then multiplying the groups of plugs to the various groups of secondary selectors, I can reverse this. That is, I can multiple each line 10 times to as many switches of different groups, such as X' —10, X^{20} , X^{30} , etc., and each group of plugs can then be multiplied to the secondary selectors X^2 in one group of 10, as shown diagrammatically in Fig. 6. Again, the lines may be multiplied to primary selectors of different groups, and the plugs may also be multiplied to secondary selectors in different groups as illustrated in Fig. 7, thus attaining even a greater distribution than I have above pointed out, for any line may be picked up and connected to any plug circuit in the whole exchange, the number of combinations possible being enormously increased.

Having thus described the principles underlying my invention, and one embodiment thereof which I now consider the best, and having also pointed out some modifications which are possible, I wish to state in closing that I am aware many other modifications and changes can be made without departing from the spirit of the invention. All such I consider within the scope and purview hereof.

Among such changes are those in the nature of the drive of the shaft, which need not be constantly driven. Various devices of clutches or electrical motors with circuit controllers and the like can be used, but as these are well understood in the art, I do not consider it necessary to illustrate or further describe them. The effect of having the motor mechanism normally idle, so that

the selector switches may have a zero point, is to land all calls first upon the first position, and so on down the board as the number of calls increases. Various other changes will occur to those versed in the art.

Having thus described my invention, what I claim and desire to secure by Letters Patent is:

1. In a telephone exchange system, means for distributing calls from incoming lines or trunks among the several units of the exchange connective apparatus, comprising primary selector switches containing answering multiples of the lines, connective units, secondary selector switches containing multiples of the circuits of the said connective units, and trunk lines connecting the primary and secondary selector switches in pairs, each pair of switches constituting an initial link between a calling line and the actual connective apparatus in the exchange, and each pair adapted to complete its function in response to a call, by connecting the calling line to an idle unit, before the performance of any act to select the wanted subscriber, substantially as described.

2. In a telephone exchange system, means for distributing calls comprising primary selector switches divided into groups, a group of line-circuits multiplied to terminal contacts in each corresponding group of primary selectors, connected units, secondary selectors connected to the primary selectors, and multiple terminals in said secondary selectors for the connective units, each pair of primary and secondary selector switches adapted to complete its function of connecting a calling line to an idle connective unit as a preliminary to the selection of the wanted subscriber, substantially as described.

3. In a telephone exchange system, means for distributing calls comprising automatic primary and secondary selector switches, line-terminals in the former, and connective-circuit terminals in the latter, a switching member for each primary selector switch with an electromagnet to actuate the same and means controlled by the calling line to energize said magnet, together with a switching member for each secondary selector with a controlling electromagnet, means to energize said controlling electromagnet through said primary selector and additional energizing means for said controlling electromagnet including connective circuit terminals of said secondary switch.

4. In a telephone exchange system, means for distributing calls comprising automatic primary and secondary selector switches, line-terminals in the former, and connective-circuit terminals in the latter, a switching member for each primary selector switch with an electromagnet to actuate the same and means controlled by the calling line to energize said magnet, together with a switch-

- ing member for each secondary selector with a controlling electromagnet, means to energize said controlling electromagnet controlled by the operation of the primary selector, and additional energizing means for said controlling electromagnet including terminals of connective circuits which are not in use, substantially as described. 5
5. In a telephone exchange system, a subscriber's station and a metallic circuit extending therefrom to a central station, connective units at the central station, an individual relay and battery connections for the line at the central station, a primary selector switch containing talking circuit terminals and testing means for the line, said line-relay controlling the condition of the said testing means, a secondary selector switch connected to the primary selector and containing multiple talking circuit terminals and testing means for the connective units, and means for actuating both primary and secondary selector switches, said means also controlled initially by the individual relay of the calling line, whereby the switches will automatically establish connection from the line to an idle connective unit, substantially as described. 10
6. In a telephone exchange system, a plurality of line-circuits and a plurality of link-circuits for interconnecting the lines, together with intermediate means for distributing the calls among and uniting the lines when calling to the link-circuits, comprising the following instrumentalities: a primary selector switch containing line-terminals and test terminals therefor, a secondary selector switch containing link-circuit terminals and test terminals therefor, a controlling magnet 35 for each switch energized through the test terminals, a line relay and source of current for each line energized in response to a call to change the condition of its test terminal in the primary selector switch to thereby put the same in connection with the calling line, a relay associated with the primary selector and acting upon operation of the latter to render operative the circuit of the controlling magnet of the secondary selector, a relay associated with each link-circuit adapted to change the condition of its test terminal and to operate said secondary selector when the link is idle, and means whereby after connection between two subscribers is completed, the calling subscriber may control the circuits of both selectors, substantially as described. 40
7. In a telephone exchange system, a selector switch normally disconnected from the lines, means to connect the same so as to form the terminal of a calling subscriber's line and a plurality of link-circuits having terminals in said switch, a controlling magnet for the switch and a pair of relays for each link jointly controlling the condition 45
- of the test terminal thereof, one of said relays responding to current in the calling end of the circuit only, and the other relay controlled by an operator in the use of the link-circuit, substantially as described. 50
8. In a telephone exchange system, a subscriber's metallic line-circuit and multiple connection terminals therefor at a central office, normally disconnected from the line, certain of said terminals being spring-jacks 75 for manual connection, and an automatic switch containing one or more of the other terminals, together with a cut-off relay adapted when energized to connect the line to the terminals, means controlled through the automatic switch or the jacks to energize said cut-off relay, and means associated with the switch to maintain the same in connection with a line after the cut-off relay is energized, substantially as described. 80
9. In a telephone exchange system, line circuits, a trunk circuit and a cord circuit, a primary selector switch having a controlling solenoid and traveling contacts and provided with stationary line contacts, trunk contacts and solenoid control contacts, a secondary selector switch having a controlling solenoid and traveling contacts and being provided with stationary trunk contacts, cord circuit contacts and solenoid control contacts, a common source of current, and means for effecting the interconnection of the line circuits through said trunk and cord circuits by means of said primary and secondary selector switches. 85
10. In a telephone exchange system, a plurality of subscribers' lines, a number of operators' circuits less than the number of lines, and selector switches containing multiple contacts of both the lines and the operators' circuits, together with means associated with said switches and responsive to current changes in calling subscribers' lines adapted to automatically connect the same with idle operators' circuits. 90
11. In a telephone exchange system, a plurality of subscribers' lines, an operator's circuit, a calling signal associated with said circuit, and an automatic switching apparatus normally disconnected but containing a terminal of each line and of the operators' circuits, and responsive to current change in a calling line to connect the same to the operator's circuit and to display the operator's signal, substantially as described. 95
12. In a telephone exchange system, a plurality of subscribers' lines, operators' circuits less in number than the number of lines, a calling signal for each operator's circuit, and automatic switching apparatus 105 containing terminals of the lines and also containing terminals of the operators' circuits, said switching apparatus adapted when a line is calling to automatically select and connect said line and an idle operator's 110
13. In a telephone exchange system, a plurality of subscribers' lines, operators' circuits less in number than the number of lines, a calling signal for each operator's circuit, and automatic switching apparatus 115 containing terminals of the lines and also containing terminals of the operators' circuits, said switching apparatus adapted when a line is calling to automatically select and connect said line and an idle operator's 120
14. In a telephone exchange system, a plurality of subscribers' lines, operators' circuits less in number than the number of lines, a calling signal for each operator's circuit, and automatic switching apparatus 125 containing terminals of the lines and also containing terminals of the operators' circuits, said switching apparatus adapted when a line is calling to automatically select and connect said line and an idle operator's 130

circuit, at the same time displaying the associated calling signal, substantially as described.

13. In a telephone exchange system, a plurality of line circuits, a number of link circuits less than the number of lines adapted to interconnect the same for conversation, a number of operators' calling signals also less than the number of lines, automatic switching apparatus containing multiple terminals in both the lines and the link circuits, means responsive to current change in a calling line for causing the switching apparatus to select said line and also to select an idle operator's signal and an idle link circuit, and means whereby the operator may communicate with the calling subscriber and manually complete the connection desired, substantially as described.
14. A telephone system including telephone lines, manually controlled operators' connecting apparatus and a link-circuit having automatically controlled active terminals at one end to select the line and similar terminals at the other end to select the connecting apparatus.

15. A telephone system including a plurality of telephone lines, a less plurality of operators' signals at the exchange and a link-circuit having automatically controlled active terminals at either end to respectively select the calling line and select and display one of said signals.

16. A telephone system including telephone lines, a smaller number of operators' signals at the exchange and mechanism for automatically temporarily associating said signals with calling lines comprising link-circuits adapted to select said signals and automatically controlled means for connecting any one of said link-circuits with any one of said lines as a calling line.

17. A telephone system comprising telephone lines provided with multiple terminals at the exchange normally unselectable in character, mechanism operative when a

subscriber initiates a call to render the terminals of his line selectable, manually controlled operators' connecting apparatus at the exchange provided with multiple terminals normally selectable in character, a link-circuit provided with electrically controlled selectors at each end operated respectively to the initiation of a call to respectively select terminals of the calling line and of the first idle connecting apparatus to connect said apparatus and line, and means automatically effective to thereon render both sets of terminals unselectable in character.

18. A telephone system comprising telephone lines, manually controlled operators' connecting means, and selector switches connected in pairs, one switch of a pair being adapted to select the calling line and the other to select the first idle connecting means.

19. A telephone system including telephone lines, multiple spring-jacks for said lines at the exchange, operators' cords for connecting with said spring-jacks, call signals associated with said cord-circuits, and selector switches connected in pairs, one switch of a pair being adapted to select the calling line and the other to select the first idle cord and display its signal.

20. A telephone system comprising a group of telephone lines, a group of operators' connecting apparatus for interconnecting said lines and an intermediate link-circuit provided with automatically controlled mechanism for interchangeably connecting one end of said link with the lines of the group and the other end interchangeably with the connecting apparatus of the group.

In testimony whereof I have affixed my signature in presence of two witnesses.

EDWARD E. CLEMENT.
